United States Patent Office.

A. J. SPRAGUE, OF TOLEDO, OHIO, ASSIGNOR TO HIMSELF AND PAUL JONES, OF THE SAME PLACE.

Letters Patent No. 66,408, dated July 2, 1867.

IMPROVED BRICK MACHINE.

The Schedule referred to in these Letters Patent and making part of the same.

TO ALL WHOM IT MAY CONCERN:

Be it known that I, A. J. SPRAGUE, of Toledo, in the county of Lucas, and State of Ohio, have invented a new and improved Machine for Moulding and Pressing Bricks, and that the following description, taken in connection with the accompanying drawings hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention relates to a new and improved machine for moulding and pressing bricks, and it consists in a novel means for pressing the clay into the moulds, with a feeding and discharging device, and a guard-grating, as hereinafter set forth, whereby clay may be moulded and pressed into proper form very expeditiously and in a perfect manner. In the accompanying sheets of drawings—

Figure 1, Sheet No. 1, is a front elevation of my invention.

Figure 2, a vertical section of the same taken in the line *xx*, fig. 1.

Figure 3, Sheet No. 2, a horizontal section of the same taken in the line *yy*, fig. 2.

Figure 4, a horizontal section of the press-box taken in the line *zz*, fig. 2.

Similar letters of reference indicate like parts.

A represents a frame of rectangular form, and constructed in any proper manner to support the working parts. In the upper part of this frame *A* the mud-mill *B* is placed; the sides of the case of which are secured in the frame. This mud-mill, as usual, is provided with a vertical central shaft, *C*, having horizontal arms *D* extending therefrom, to pulverize and temper the clay, and the bottom *a* of the mud-mill has a rectangular opening, *b*, made in it, over which the tempered clay passes into the press-box *F*. This press-box *F* contains the presser *G*, which is composed of a curved arm or blade extending from a shaft, *H*, which passes horizontally through the press-box *F*, and has a bevel-wheel, *I*, on one end of it into which a bevel-wheel, *J*, on the lower end of a shaft, *K*, gears, the latter having its bearings at one side of the frame *A*. On the upper end of the shaft *K* there is secured a bevel-pinion, *L*, into which a bevel-pinion, *M*, gears, the latter being on a horizontal shaft, *N*, from which the mud-mill shaft *C* is driven by bevel-gears *O*. In the bottom of the press-box *F* there is fitted a grating, *P*, through which the tempered clay is forced into the mould-box *Q*. The presser *G* rotates in the direction indicated by the arrows in fig. 2, and the mould-box *Q* when receiving the clay rests upon rollers *R* in a pivoted frame, *S*, underneath the press-box, said frame being pivoted at its rear end, as shown at *c*, and having its front end resting on eccentrics *d*, *d* on a shaft, *T*, shown in figs. 1 and 2. The grating *E* prevents stones and other large foreign substances from entering the press-box. The mould-boxes are fed underneath the press-box and out from underneath the same by means of a plate, *U*, which is attached by a set-screw, *e*, to a cross-bar, *V*, which is secured to two bars *W*, *W*, the latter resting on rollers *X* in the frame *A*. These bars *W*, *W* have each an upright, *Y*, secured to them, against which arms *Z*, *Z* on the shaft *H* come in contact and move the bars *W*, *W*, and consequently the plate *U* forward, the latter shoving the mould-box underneath the press-box, the plate *U* and bars *W*, *W* being drawn back by a spring, *A'*, or its equivalent. The empty mould-boxes are placed on a stationary plate, *B'*, just back of the press-box and over which the plate *U* works.

Having thus described my invention, I claim as new, and desire to secure by Letters Patent—

1. The rotary presser *G*, arranged within the press-box *F*, to operate in the manner substantially as and for the purpose set forth.
2. The grating *E* placed over the opening *b*, in the bottom of the mud-mill *B*, substantially as and for the purpose specified.
3. Operating the mould-feeding plate *U* through the medium of the revolving arms *Z*, *Z*, on the shaft *H*, the uprights *Y* on the bars *W*, *W*, and the spring *A'* or its equivalent, all arranged substantially as shown and described.

The above specification of my invention signed by me this 20th day of March, 1867.

A. J. SPRAGUE.
